UNITED STATES PATENT OFFICE.

RALPH C. SEYMOUR, OF LARCHMONT, NEW YORK, ASSIGNOR TO GOSS PRINTING PRESS COMPANY, OF CHICAGO, ILLINOIS, A CORPORATION OF ILLINOIS.

ASSOCIATING AND BINDING MACHINE.

1,213,425.

Specification of Letters Patent. Patented Jan. 23, 1917.

Original application filed July 10, 1909, Serial No. 506,956. Divided and this application filed December 8, 1911. Serial No. 664,556.

To all whom it may concern:

Be it known that I, RALPH C. SEYMOUR, a citizen of the United States, residing at Larchmont, in the county of Westchester 5 and State of New York, have invented certain new and useful Improvements in Associating and Binding Machines, of which the following is a specification.

The invention relates to machines for associating, binding and folding a plurality of sheets into a book, although certain of its 10 features are useful in other connections.

Objects of the invention are to provide for associating a plurality of sheets together 15 with either or both a cover and an insert and to make them into a book of neat appearance and to perform the necessary operations with great rapidity; to provide for performing the various operations of making 20 the books carefully and precisely but in such a relation to each other as to conduce to rapid production and a large product; to provide a novel and useful relative arrangement of mechanisms for successively acting 25 on the sheets to make the book; to provide for exact and speedy control of the sheets at and between the binding and folding positions; to provide novel trimming devices and a novel method of trimming and handling 30 the associated sheets. These and other objects of the invention will in part be obvious and will in part more fully appear herein-after.

The invention consists in the novel methods, parts, constructions, arrangements, combinations and improvements herein shown and described.

The accompanying drawings, referred to herein and forming a part hereof, illustrate 40 one embodiment of the invention, the same serving in connection with the description herein to explain the principles of the invention.

Of the drawings: Figure 1 is an elevation 45 of a machine constructed in part in accordance with the principles of the invention; Fig. 2 is an end elevation looking at Fig. 1 from the left; Fig. 3 is a horizontal section on the line A—B of Fig. 1; Figs. 4 and 5 are 50 details of certain sheet handling devices; Figs. 6, 7 and 8 are details of the sheet trimming devices; and Figs. 9 to 11, inclusive, are views showing somewhat diagrammatically the trimming and folding of a book.

Referring to the accompanying drawings, 55 illustrating by way of example one embodiment of the invention, suitable means for associating a plurality of sheets are shown. The illustrated form thereof is adapted to operate upon a plurality of webs, or the 60 various parts of a slit web. Suitable web forwarding means are provided including in the present embodiment devices for forwarding a multi-width web, and means for forwarding the slit sections thereof (which so 65 far as concerns certain features of the invention might be separate webs). In the embodied form of such means a pair of rollers 80 are shown acting upon the multi-width web which is then slit into sections by the 70 rotary slitters 81 and 82, which operate in a well known manner. After being slit, the sections of the web are forwarded so as to be superimposed together by passing over turner bars and between rollers as will now 75 be described more particularly. The three webs, or sections of web, indicated respectively by the numerals 1, 2 and 3 are shown directed into the machine and passing respectively over the turner bars 4, 5 and 6. 80 In the present instance the webs are first associated and then cut. The webs are associated by being run between the rollers 7 and 8, or in any other suitable or convenient manner. Suitable sheet forming devices are 85 provided, and the form thereof herein illustrated comprises rotary cutters 9 and 10. The bundle or stack of sheets is then directed forward by suitable means, the illustrated form thereof comprising guide or throat 90 bars 11.

According to certain features of the invention, means are provided for supplying the bundle of associated sheets either a cover, or an insert, or both. Accordingly 95 in the illustrated embodiment a form of such means is provided. As the sheets pass along they are engaged by suitable grippers upon a cylinder 12 and may be supplied at this point with a cover. So far as concerns 100 many features of the invention, the cover feeding means may be of any suitable and convenient form, and it is shown herein as comprising a feed board 13, sets of conveying tapes 14 and 15, and a suitable stop gate 105 or front gage 16. These parts coöperate in a well-known manner to feed a cover to the cylinder 12, which is taken by the grippers

upon the cylinder and is associated thereon with the sheets. The form of insert supplying means herewith shown comprises a feed board 17, sets of tapes 18 and 19 and a stop 5 gate or front gage 20, which coöperate in a manner which will be well understood to supply the inserts to the opposite side of the sheet bundle or stack from the cover when both are run at the same time. In one form 10 of the invention the insert is not fed to the cylinder, but direct to the pathway to the mechanism for the subsequent operations. In the illustrated embodiment, therefore, the tapes 18 and 19 and the gate 20 are 15 shown feeding the insert to the tapes 21 and 22. This obviates taking the insert upon the cylinder 12, and thus there is no need for a corresponding gripper movement. The risk of non-registration of the insert 20 with the sheets upon the cylinder is likewise avoided. In the present machine the insert and the sheet bundle are conveyed along by the tapes 21 and 22 and are brought independently to register against the stop 25 40. While so registered they may be accurately held and then stitched together. It will be understood, however, so far as concerns many features of the invention, both the cover and insert, or either or neither of 30 them may be run with the associated sheets as desired. If desired the cylinder 12 may be used as a collecting cylinder by suitable arrangement and operation of the grippers, and the switch or stripper 23 may be used 35 or thrown out of operation according to the way in which the mechanism is being used. The sheets are then conveyed along a path by suitable conveying means, such as sets of tapes 21 and 22, the path of travel of the 40 sheet being shown horizontally arranged. In the present embodiment means are provided for binding, trimming and folding the associated sheets, said means being arranged along the path of travel of the 45 sheets. So far as concerns certain aspects of the invention certain of these mechanisms might be omitted or certain other mechanisms provided. According to one feature of the invention means are provided 50 for binding the sheets in a longitudinal direction as referred to their path of travel. Accordingly a form of such means is shown herein comprising stitchers 24 and 25 with coöperating anvils 26^a and 27^a. 55 The form of folding means herein shown is constructed and arranged to deliver the sheets at one side of their path of travel, and, according to one feature of the invention, to fold them in a direction longitudinal of said path of travel. The particular form of folding means shown includes a folding blade 26 and folding jaws 27 which engage the sheets to fold them over the blade and then carry them away for delivery. The folding jaws 27, if desired, may

be spring pressed to hold them normally in closed position in a well-known manner. For movement between folding and delivering position they are shown mounted on arms 28 fixed to a rock shaft 29. Suitable 70 actuating devices for arms 28 are provided, such as an arm 30, link 31 and lever 32, said lever being pivoted at 32^a, operatively connected with a cam 33.

Delivery devices of suitable and convenient form are provided, and the illustrated form thereof comprises a pocket delivery 34 shown herein arranged at one side of, and also above, the path of travel of the sheets. Suitable means for causing the jaws to deliver the sheets are provided, and the form thereof shown in the drawings comprises a trip arm 35 and a suitable tripping cam 36.

In accordance with certain features of the invention, means for stopping the sheets in position for binding are provided and also means for conveying them positively from a binding to a folding position, that is, means which engage the sheets positively and control their movement accurately as distinguished from means whose action upon the sheet is indeterminate, such as devices acting only on the outer sheets and depending on the adhesion between the sheets of the bundle to keep them together. According to one feature of the invention also, means for stopping and positioning the sheets for binding acting independently of the means for conveying them from the binding to the folding position are provided. 100 By such an arrangement a second bundle or group of sheets may immediately be positioned for binding without waiting for the conveying devices to return from folding position, nor is it necessary for the folding devices to remain at rest at the binding position during the binding operation. The speed of the machine, as will be clearly understood, is thereby greatly increased. In the embodied form of these features of the invention, a gate or gage 40 is shown movable into and out of the path of travel of the sheets. The gate is suitably located with respect to the binding mechanism to present the sheet bundle in proper binding position when it is brought to rest against the gate. Said gate is shown mounted upon swinging arms 41, connected by pivoted links 42 to lever arms 43, acted upon by a suitable cam 44. A set of traveling grippers 45 is shown reciprocable between the binding and folding positions. These grip or clamp the sheet bundle firmly at the binding position and carry it to, and bring it to rest in proper position with respect to, the folding devices. Said grippers are shown mounted upon a supporting bar or cross-head 46, sliding on ways 72, and connected by pivoted links 47 to levers 48, in operative relation with a cam 49. Suitable means for con-

trolling the opening and closing action of these grippers may be provided at both the binding and folding positions if desired, and they may be generally of the form already shown and described in connection with the folding jaws. Springs 50 are shown pressing the jaws together, and trip fingers 51 and 52 which coact with cam pieces 53 and 54 to open the jaws against their springs may be provided.

5 The invention in one of its aspects provides means for trimming the edges of the book in such a manner that notwithstanding the sheets are of equal width and are folded one within the other successively, the edge of the folded book opposite the back will be substantially straight or uniform. According to one feature of the invention, the trimming means acts upon the sheets previous to 10 their being folded and in accordance with a further feature of the invention said means act to trim the sheets at the folding position and without any stoppage of the folding mechanism. The trimming means is shown, 15 accordingly, constructed and arranged to trim the edges of the extended or unfolded sheets obliquely or slantingly. Thus the inner sheets are cut just sufficiently smaller than the outer to compensate for the thickness of the successive unfolded sheets and so 20 to present a straight edge after the fold is made. The illustrated form of such means shown herein comprises blades or shears 55 traveling in suitable blocks or guides 56. 25 These may be arranged, if desired, with slots 69 in which travel pins 70 on the blades. The blades may be acted on by cams 57 to which they are held by springs 58, shown herein between the pins 70 and lugs 71 on 30 the guides 56. The blades or cutters 55 move obliquely relatively to the plane of the sheets, and may work along the edges of a suitable support or table 59. Suitable means are provided for clamping or otherwise 35 holding the edges of the sheets firmly in position during the trimming operation. The illustrated form thereof comprises clamping bars 60 for closing down upon the sheets, and moving away after the trimming operation to free them for delivery. The bars 40 60 may be provided with a beveled edge 61, if desired, to aid in giving a clean cut during the trimming. The clamps 60 are shown mounted upon swinging arms 62, connected 45 to the shaft 63. The shaft 63 is shown having fixed thereto an arm 65 in operative relation with a cam 66. If desired a yielding clamping action may be secured. A form 50 of means for effecting this is accordingly provided. The form thereof shown comprises collars 69 fixed to the arms 62 and 55 loosely mounted on shaft 63. Collars 69 are provided with lugs 67 in alinement with stops 68 on shaft 63, against which they are 60 impelled by springs 64.

The manner of operation of the herein-described mechanism is substantially as follows: The slit web or webs are run over the turner bars 4, 5 and 6 and are associated between the rolls 7 and 8 and are severed 70 into bundles or stacks of sheets by the rotary cutters 9 and 10. They are then directed to the throat 11 and the cylinder 12. If a cover is to be supplied it will be released 75 in proper relation by the gate 16 and taken up by the cylinder. The insert, when run, will also be supplied upon the opposite side of the sheet bundle by the mechanisms already described. After one or more revolutions of the cylinder 1, and with or without 80 either the cover or insert, or both, the sheets are then conveyed along the path by the tapes 21 and 22, and are brought to rest in position for binding by the stop gate 40. They are then operated upon by the stitchers 85 24 and 25 which bind them together. The grippers 45 are reciprocated to and fro along their path of travel and grip the sheets while positioned against the gate 40. The gate 40 is then swung downwardly 90 and the gripped sheets are conveyed along their path and brought to rest in position over the folding blade 26 by the grippers 45. The clamps 60 close down upon the edges of the sheet and press them against 95 the table or support 59 and the blades 55 move upward obliquely and trim off the edges of the sheets. The folding jaws, swinging downwardly with their arms 28, fold the sheets over the blade 26 and the 100 sheets, having been released by the clamps 60 and the grippers 45, are swung upwardly in the bite of the folding jaws to position above the folding pockets 34. The jaws are now opened by the action of the trip 36 105 upon the finger 35 and the book falls into the pocket upon the conveyer 34.

From all the foregoing it will be understood that a machine has been provided embodying and illustrating the principles of 110 the invention and realizing the objects of invention and the advantages herein set forth, together with other objects and advantages.

The invention, in its broader aspects, is 115 not limited to the particular constructions shown, nor to any particular constructions by which it has been or may be carried into effect, as many changes may be made in the construction without departing from the 120 main principles of the invention and without sacrificing its chief advantages.

This application is a division of my co-pending application Ser. No. 506,956, filed July 10, 1909, now Patent No. 1,011,864, December 12, 1911.

What I do claim as my invention and desire to secure by Letters Patent, is:

1. The combination with web forwarding means, of devices for severing sheets from 130

the webs, sheet forwarding means including timing devices located on one side of the web forwarding means, sheet forwarding means including timing devices located on the other side of said web forwarding means, means for assembling sheets from said sheet forwarding means with the web sheets and upon both sides of the web sheets, longitudinally arranged means for stitching the assembled sheets, and means for stopping the sheets while being stitched.

2. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets and upon both sides of the web sheets and a plurality of stitching devices arranged longitudinally of the direction of travel of the sheets for stitching the assembled sheets.

3. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets and upon both sides of the web sheets, a plurality of stitching devices arranged longitudinally of the direction of travel of the sheets for stitching the assembled sheets, means for stopping the sheets while being stitched and means for folding the stitched sheets.

4. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets and upon both sides of the web sheets, means for stitching the assembled sheets with a plurality of stitches arranged longitudinally of the direction of travel of the sheets, means for stopping the sheets while being stitched, means for conveying the stitched sheets to a folding mechanism, and a folding mechanism for folding the stitched sheets along said stitches.

5. The combination with web forwarding means, of devices for severing sheets from the webs, sheet forwarding means including timing devices located on one side of the web forwarding means, sheet forwarding means including timing devices located on the other side of said web forwarding means,

means for collecting sheets cut from the web, means for assembling sheets from said sheet forwarding means with the web sheets, a tape pathway into which the collected sheets are progressed from said collecting means, and stitching means located along said tape pathway and adapted to make a plurality of stitches in the sheets longitudinally of their direction of travel.

6. The combination with web forwarding means, of devices for severing sheets from the webs, sheet forwarding means including timing devices located on one side of the web forwarding means, sheet forwarding means including timing devices on the other side of said web forwarding means; means for collecting sheets cut from the web, means for assembling sheets from said sheet forwarding means with the web sheets, a tape pathway into which the collected sheets are progressed from said collecting means, and a stationary stitching means located along said tape pathway and adapted to make a plurality of stitches longitudinally of the direction of travel of the sheets.

7. The combination with web forwarding means, of devices for severing sheets from the webs, sheet forwarding means including timing devices located on one side of the web forwarding means, sheet forwarding means including timing devices located on the other side of said web forwarding means, means for collecting sheets cut from the web, means for assembling sheets from said forwarding means with the web sheets, a tape pathway into which the collected sheets are progressed from said collecting means and a stationary stitching means located along said tape pathway and means for momentarily stopping the sheets to be stitched to receive a plurality of stitches longitudinally of their direction of travel.

8. The combination with web forwarding means, of devices for severing sheets from the webs, sheet forwarding means including timing devices located on one side of the web forwarding means, sheet forwarding means including timing devices located on the other side of said web forwarding means, means for collecting sheets cut from the web, means for assembling sheets from said sheet forwarding means with the web sheets, and a tape pathway into which the collected sheets are together progressed directly from said collecting means, and a folding mechanism receiving the sheets from said pathway.

9. The combination with web forwarding means, of devices for severing sheets from the webs, sheet forwarding means including timing devices located on one side of the web forwarding means, sheet forwarding means including timing devices located on the other side of said web forwarding means, means for assembling sheets

from said sheet forwarding means with the web sheets and upon both sides of the web sheets, means for stitching the assembled sheets at a plurality of places longitudinally 5 of their direction of travel, and means for presenting the assembled sheets flat to the stitching means.

10. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets and upon both sides of the web sheets, reciprocating means for stitching the assembled sheets at a plurality of places 15 longitudinally of their direction of travel and means for presenting the assembled sheets flat to the stitching means.

11. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets, a flat horizontal pathway to which the assembled sheets are progressed, and stitching means for the assembled sheets 20 longitudinally of places 25 of their direction of travel and means for presenting the assembled sheets flat to the stitching means.

12. The combination with web forwarding means, of devices for severing sheets from the webs, sheet forwarding means including

40 timing devices located on one side of the web forwarding means, sheet forwarding means including timing devices located on the other side of said web forwarding means, means for assembling sheets from said forwarding means with the web sheets, a flat horizontal pathway to which the assembled sheets are progressed, a plurality of stationary stitching devices for the assembled sheets located longitudinally of said pathway, and means for momentarily stopping 45 the sheets to be stitched.

13. The combination with web forwarding means, of devices for severing sheets from the webs, sheet forwarding means including 55 timing devices located on one side of the web forwarding means, sheet forwarding means including timing devices located on the other side of said web forwarding means, means for assembling sheets from said sheet forwarding means with the web sheets, a flat horizontal pathway to which the assembled sheets are progressed, stitching means for the assembled sheets including a plurality of stitching devices arranged longi-

tudinally of said pathway and driving the staples through from above.

14. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets, a flat horizontal pathway to which the assembled sheets are progressed, stitching means for the assembled sheets including a plurality of stitching devices arranged longitudinally of said pathway driving the staples through from above and means for folding the stitched sheets upwardly.

15. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets, a flat horizontal pathway to which the assembled sheets are directly progressed from said assembling means, and stitching means for the assembled sheets located along said pathway and adapted to make a plurality of stitches longitudinally of the sheets.

16. The combination with web forwarding means, of devices for severing sheets from the webs, sheet forwarding means including timing devices located on one side of the web forwarding means, sheet forwarding means including timing devices located on the other side of said web forwarding means, means for assembling sheets from said forwarding means with the web sheets, a flat horizontal pathway to which the assembled sheets are directly progressed from said assembling means, stationary stitching means for simultaneously forming a plurality of stitches longitudinally of the assembled sheets and means for momentarily stopping the sheets to be stitched.

17. The combination with web forwarding means, of devices for severing sheets from the webs, sheet forwarding means including timing devices located on one side of the web forwarding means, sheet forwarding means including timing devices located on the other side of said web forwarding means, means for assembling sheets from said sheet forwarding means with the web sheets, a flat horizontal pathway to which the assembled sheets are directly progressed from said assembling means, a plurality of stitching devices for the assembled sheets located in succession along said pathway, and driving the staples through from above.

18. The combination with web forwarding means, of devices for severing sheets from the webs, sheet forwarding means including timing devices located on one side of the 5 web forwarding means, sheet forwarding means including timing devices located on the other side of said web forwarding means, means for assembling sheets from said sheet forwarding means with the web sheets, a flat 10 horizontal pathway to which the assembled sheets are directly progressed from said assembling means, a plurality of stitching devices for the assembled sheets located in succession along said pathway driving the 15 staples through from above and means for folding the stitched sheet upwardly.

19. The combination of means for cutting sheets from a web, a cylinder for collecting the cut sheets, means for progressing the collected sheets along a pathway away from said cylinder, and means for assembling extra sheets at each side of the collected web sheets, said assembling means including devices for introducing a sheet at the 25 juncture between said cylinder and said pathway.

20. The combination with means for cutting a plurality of sheets from a web and collecting them, stitching means, means for progressing sheets along a pathway, and means for assembling an extra sheet on each side of the collected web sheets, said assembling means including devices for introducing an extra sheet between the web 35 sheet collecting means and the stitching means.

21. The combination with means for cutting a plurality of sheets from a web and collecting them, of means for assembling an extra sheet on each side of the collected sheets, means for progressing said collected and assembled sheets together along a pathway, and a plurality of stitching devices arranged longitudinally of said pathway. 40

45 22. The combination with means for cutting a plurality of sheets from a web and collecting them, of means for assembling an extra sheet on each side of the collected sheets, means for progressing said collected

and assembled sheets together along a pathway, and a plurality of simultaneously operable stitching devices arranged longitudinally of said pathway. 50

23. The combination with means for cutting a plurality of sheets from a web and collecting them, of means for assembling an extra sheet on each side of the collected sheets, means for progressing said collected and assembled sheets together along a pathway, and a plurality of stationary stitching devices arranged longitudinally of said pathway. 55

24. The combination with means for cutting a plurality of sheets from a web and collecting them, of means for assembling an extra sheet on each side of the collected sheets, means for progressing said collected and assembled sheets together along a pathway, and a plurality of stationary and simultaneously operable stitching devices arranged longitudinally of said pathway. 60

25. The combination with means for cutting a plurality of sheets from a web and collecting them, of means for assembling an extra sheet on each side of the collected sheets, means for progressing said collected and assembled sheets together along a pathway, and stitching means adapted to make a plurality of staple stitches through said sheet along the direction of their travel. 70

26. The combination with means for cutting a plurality of sheets from a web and collecting them, of means for assembling an extra sheet on each side of the collected sheets, means for progressing said collected and assembled sheets together along a pathway, and stitching means adapted to make a plurality of staple stitches through said sheet along the direction of their travel while at rest in said pathway. 80

90 In testimony whereof, I have signed my name to this specification, in the presence of two subscribing witnesses.

RALPH C. SEYMOUR.
